UNITED STATES PATENT OFFICE.

WILLIAM PHILANDER FISHER AND HARLEY PULASKI LUDINGTON, OF MUNCIE, INDIANA.

FRUIT-JAR OR BOTTLE MACHINE.

SPECIFICATION forming part of Letters Patent No. 701,188, dated May 27, 1902.

Application filed October 24, 1900. Serial No. 34,170. (No model.)

To all whom it may concern:

Be it known that we, WILLIAM PHILANDER FISHER and HARLEY PULASKI LUDINGTON, citizens of the United States, residing at Muncie, in the county of Delaware and State of Indiana, have invented a new and useful 5 Fruit-Jar or Bottle Machine, of which the following is a specification.

Our invention relates to glass-blowing machines, and more particularly to a machine for forming fruit-jars and bottles, &c., and has for its object to produce a machine of this kind in which the melted glass can be easily placed and quickly formed into the desired object; and it consists in the improved construction and novel arrangement of parts of the same, as will be hereinafter more fully set forth.

In the accompanying drawings, in which the same reference-numerals indicate corresponding parts in each of the views in which they occur, Figure 1 is a side elevation, partly in section, of a machine embodying our invention. Fig. 2 is a top plan view of the same; and Figs. 3 and 4 are front views of the mold, showing it in two positions.

Our machine is preferably supported by a column 1, that has its lower end flanged and bolted or otherwise secured to a base-plate 2. The intermediate portion of the column is provided with a collar 3, upon which is supported, preferably by ball-bearings 4, the lower end of a hub 5 of a flat horizontally arranged plate 6. A circular way 7 is secured to the hub of the plate in any suitable manner, as by brackets 8. The lower edge of the way, which is arranged concentric with the column 1, is provided with a series of notches 9, by means of which the way and the plate or table 6 may be rotated by means of a pawl 10 in a reciprocating head 11, that is secured to the outer end of the piston 12 of an air-cylinder 13. The cylinder is pivotally mounted upon a bracket 14 on the base, so that the head may follow the movement of the circular way as it is moved back and forth by the piston, and the head is pivotally secured to the piston, as by means of a pin 15. The pawl 10 is arranged to reciprocate within the head and has its lower end reduced and passed through a bracket 16. A

spring 17 encircles the lower end of the pawl and engages with the bracket and the shoulder of the pawl at the end of the reduced portion to normally force the upper end of 55 the pawl into engagement with the notched surface of the way. The length of the stroke of the piston is regulated by a set-screw 18 at the outer end of the cylinder, and the cylinder is provided with a three-way valve 19, 60 which is provided with two inlet-ports and one exhaust-port for the purpose of reducing the pressure upon one end of the cylinder. The cylinder is preferably reinforced on the side where the ports lead from the valve to 65 the ends of the cylinder.

Mounted upon the upper surface of the table 6, which is preferably made angular, five sides or angles being shown in the drawings, are suitable glass-blowing apparatus, one for 70 each side of the table, one only being shown in the drawings, as said mechanisms are all alike. A shaft 20 is journaled in suitable bearings 21 on top of the table, and a disk 22 is secured to the outer end of the shaft, so as 75 to overhang that edge of the table. A two-part mold 23 is hinged to the disk, as shown at 24, so that it may be opened for the removal of the article after it has been blown. The parts of the mold are held together in 80 any suitable manner, as by means of arms 25, which project from the forward portion thereof in position to be grasped by the operator. One end of each part of the mold is provided with a pin 26, which fits in a groove 27 in the 85 under side of a plate 28 and causes the mold when closed to stand centrally relatively to a plunger 29, said plate being secured to a bracket 30, that projects from the disk 22.

The bottom 31 of the mold is removable and 90 is held in position relatively to a lever or handle 32 by means of pins 33. A stem 34 from the bottom passes up through the lever and is provided at its upper end with a notch 35, in which a cam 36 on the side of a rotary post 95 37 is moved for the purpose of raising and lowering the bottom of the mold. The post 37 is rotated in its bearings by means of a handle 38, and the face of the bottom 31, which engages with the ends of the molds, is 100 preferably recessed or shouldered, as shown at 39, to engage with a corresponding shoul-

der on the molds to assist in holding the molds together and making a tight joint at the end of the mold. The lever 32 is pivotally secured to the disk, so as to be swung to one side when the bottom has been raised from the mold for the insertion of the glass from which the article is to be formed. A set-screw 40 is located in position, as in a bracket 41, to limit the return movement of the lever 10 and cause it to be stopped with the bottom directly above the bottom of the mold, so that when the handle 38 is rotated the bottom 31 will be forced into proper engagement with the bottom of the mold.

15 The bracket 30 is preferably secured to the disk, substantially midway of its ends, with the mold 23 upon one side and the plunger 29 upon the other, the plunger being journaled in a bearing 42 and provided with a head 43 at its inner end and a pinion 44 near its outer end. The plunger is hollow and terminates at its inner end in the head 43, which is of the same diameter as the internal diameter of the neck of the article being formed. The 25 plunger is provided with a hollow valve-stem 45, which is provided with a mouthpiece 46 for the reception of the blowpipe, which may be of any ordinary construction and is not shown. The inner end of the stem is provided with a conical head 47, which is adapted to fit against the head 43 of the plunger, and is perforated at the inner end of the head, as shown at 48, whereby the perforations are closed when the heads are in contact, but are opened when the head of the 35 valve-stem is forced inward away from the head of the plunger.

A spring 49 surrounds the valve-stem and engages at its outer end with a nut or collar 50, which is adjustably secured upon the stem for the purpose of holding the head at the inner end of the stem against the head of the plunger. The pinion 44 is secured to the outer end of the plunger, so as to permit of 45 a slight longitudinal movement of the plunger through the pinion, as by making the plunger angular in cross-section.

Two brackets 51 and 52 are adjustably secured to the edge of the table 6 in position to 50 support two segments 53 and 54 at right angles to the plane of the table. One of the segments 53 has its outer face provided or formed into a rack 55, which is adapted to engage with and rotate the pinion 44 as the 55 disk 22 is rotated by means of the shaft 20. The other segment 54 is provided with a slot or groove 56, which extends from end to end and has one end arranged at a greater distance from the center of the disk or the axis 60 of its rotation than the other. A collar 57 is adjustably secured upon the outer end of the plunger, as by means of a set-screw 58, and has a trunnion in position to enter the groove 56 and is preferably provided with an anti-friction-roller 59. When constructed in this 65 manner, the rotation of the shaft 20 will invert the disk 22, which will cause the pinion

44 to travel around the rack 55, which will rotate the plunger in its bearings. It will also cause the trunnion of the collar 57 to 70 pass around the cam-shaped groove 56, which will cause the plunger to be moved lengthwise into the mold as it is rotated, thereby causing the glass, which has been dropped into the top of the mold when the mold was 75 inverted, to be crowded into the neck of the mold and give it the proper shape, and especially where the neck is to be provided with screw-threads, as in fruit-jars. After the mold has been turned in its upright position 80 by this movement of the parts the mouth-piece is connected with the blowing mechanism, whereby the glass will be blown out against the sides of the mold as it gradually settles to the bottom, thus forming a complete article, which can be subsequently removed from the molds when they are separated.

Rigidly secured upon the shaft 20 between the bearings 21 is a pinion 60, which is adapted to engage with and be rotated by a vertically-movable rack 61, which is mounted in a bracket 62 upon the table 6. The rear face of the rack is preferably provided with a dovetailed rib 63, which fits in a corresponding groove in the front of the bracket. The upper end of the rack is provided with a laterally-extending arm 64, which is adapted to fit within a cam-shaped groove 65, formed in the periphery of a circular track 66. If desired, the arm may be provided with anti-friction-bearings 67. The track is secured to the column 1, near its upper end, by means of a spider 68. The track is provided with two inclined or cam-shaped portions, one of which, 69, is shown in Fig. 1, for the purpose of moving the rack twice for every rotation of the column, and the length of each of said cammed surfaces is just sufficient to cause the shaft 20 to be rotated one-half of a revolution for each reciprocation or longitudinal movement of the rack, and the parts are so arranged relatively to each other that each reciprocation or rotation of the shaft will be completed when the table has been brought 115 to a standstill after two of its movements. The shaft 20 may be removably held in its bearings by means of a collar 70, which is secured upon its inner end in any suitable manner to engage with the inner bearing 21, the hub of the disk engaging with the outer bearing and preventing longitudinal movement of the shaft.

In operating our improved glass-blowing machine the table is rotated until one of the 125 disks stands with the bottom of the mold upward. The bottom of the mold is then swung to one side and the charge of glass is inserted and permitted to fall down upon the conical end of the head of the plunger in the neck of the mold. The piston of the air-cylinder is then forced outward, which will cause the table to be given a partial rotation by means of the pawl in the head of the piston. During

- this rotation of the table the disk is inverted and the plunger forced into the neck of the mold by a rotary or spiral movement, which will force the glass into the neck of the mold.
- 5 By the time the table reaches the limit of its movement the disk has been inverted and the mold placed with its neck uppermost, which will cause the glass to gradually settle to the bottom of the mold. The mouthpiece of the
- 10 plunger is connected with the source of air, and the valves or lateral openings in the head of the plunger are opened by forcing the valve-stem inward, which will permit the air to enter the mold and blow the glass while it
- 15 is still hot. As soon as the article has been blown the mouthpiece is disconnected from the source of air and the valve-stem is drawn outward by the action of the spring around its outer portion. As soon as the glass has
- 20 been blown the table is given another forward movement by the air-cylinder, which will cause the disk to be returned to its normal position with the bottom of the mold upward. The bottom is then removed from the
- 25 mold, the molds are opened and the article removed, after which the table makes the desired number of movements, preferably two, to permit the molds to cool sufficiently before another charge of glass is inserted. By pro-
- 30 viding each edge or side of the table with a disk and means for rotating it five articles may be produced for each rotation of the table, as each set of blowing mechanisms will be operated in the same manner as soon as the arm
- 35 on the vertical rack of the table comes into engagement with the same portion of the cam, the cam being rigidly secured against rotation at the upper end of the column.
- As the parts of the machine as above de-
- 40 scribed can be arranged very compactly, the machine will occupy but little space, and the parts are so simple and can be constructed in such a substantial manner that they will not be liable to be broken or disarranged. It is
- 45 evident that jars or bottles may be rapidly produced with the help of but few attendants, who need not necessarily be skilled in the art of glass-blowing, and the articles thus produced will be of a superior quality owing to
- 50 the manner in which the plunger is inserted into the neck and the article is blown as the glass is settling to the bottom of the mold.
- Although we have shown what we consider a very desirable form of constructing our im-
- 55 proved glass-blowing machine, yet we reserve the right to make such changes and alterations therein as will come within the scope of our invention.
- Having thus fully described our invention,
- 60 what we claim as new, and desire to secure by Letters Patent, is—
1. A glass-blowing machine, comprising an oscillatory support, a mold having a removable bottom and carried by the support, a plunger also carried by the said support and provided with means for admitting air therethrough into the mold, means for oscillating
- the support, and means controlled by the oscillation of the support for simultaneously reciprocating and rotating the plunger, as set forth.
2. A glass-blowing machine comprising an oscillatory support, a mold having a movable bottom and carried by the support, a plunger also carried by the support, a hollow valve-stem in the plunger and adapted to receive air from an air-forcing device, means for oscillating the support and means for simultaneously reciprocating and rotating the plunger, said means being controlled by the means for oscillating the support, as set forth.
3. In a glass-blowing machine, a table, a disk mounted thereon so as to overhang the edge, a separable mold hinged to the disk and adapted to be inverted as the disk is rotated, the bottom of the mold being removable and adapted to engage with the parts of the mold and hold them together, a plunger carried by the disk and means for simultaneously rotating the disk and reciprocating and rotating the plunger, substantially as described.
4. In a glass-blowing machine, a table, an oscillatory disk mounted thereon, a separable mold hinged at one end of the disk, the bottom of the mold being removable, a lever adjacent to the bottom of the mold, a stem from the bottom through the lever, means for moving said stem through the lever, and a hollow plunger adapted to enter the opposite end of the mold, substantially as described.
5. In a glass-blowing machine, a table, an oscillatory disk mounted thereon, a separable mold at one end of the disk and a plunger at the other, the bottom of the mold being removable and provided with guides and a notched post, a lever pivotally secured to the disk adjacent to the bottom, the guides and the post passing through said lever, a rotary post upon the lever provided with a cam in position to engage with the notch of the post from the bottom of the mold, and a handle for operating said cam, substantially as described.
6. In a glass-blowing machine, a table, an oscillatory disk mounted thereon, a two-part mold hinged to one end of the disk and a plunger mounted upon the other end, the lower end of the mold being provided with a shoulder, a shouldered bottom detachably connected with the bottom of the mold, a swinging lever pivotally secured to the disk and provided with means for moving the bottom toward and from the bottom of the mold, and an adjustable stop in position to engage with the lever and limit its movement when the shoulder of the bottom is in position to engage with the shoulder upon the lower end of the mold, substantially as described.
7. In a glass-blowing machine, a table, an oscillatory disk mounted thereon, a bracket secured near the center of the disk, a plate secured to the bracket and provided with grooves, a two-part mold hinged to the disk, each part being provided with a pin in posi-

tion to be moved into said grooves, a removable bottom for the mold, and a rotary and reciprocatory plunger mounted upon the disk with its axis coincident with the axis of the mold, substantially as described.

8. In a glass-blowing machine, a table, an oscillatory disk mounted thereon, one end of which is provided with a mold and the other end is provided with a rotary and longitudinally-movable plunger, means for oscillating the disk and means controlled by the means oscillating the disk for simultaneously rotating the plunger and moving it longitudinally, substantially as described.

15 9. In a glass-blowing machine, a table, an oscillatory disk mounted thereon, one end of which is provided with a mold and the other end with an oscillatory and longitudinally-movable plunger, a pinion and a trunnion at 20 the outer end of said plunger, and a segmental rack and cam for engaging with said pinion and trunnion respectively as the disk is oscillated, substantially as described.

10. In a glass-blowing machine, a table, an 25 oscillatory disk mounted thereon provided with a mold at one end and a hollow plunger at the other, a pinion loosely mounted against rotation upon the plunger near its outer end, a collar rigidly secured to the plunger beyond 30 the pinion and provided with a trunnion, brackets upon the table, and two segments secured to said brackets, one of which is provided with a rack for engaging with the pinion and the other one is provided with a cam-shaped groove for engaging with the trunnion upon the collar, substantially as described.

11. In a glass-blowing machine, a table, an oscillatory disk mounted thereon provided with a mold at one end and a hollow plunger 40 at the other, the inner end of the plunger being provided with a head, a reciprocatory valve-stem in the plunger, the outer end of which is provided with a mouthpiece, and the inner end is perforated and provided with a 45 conical head, and yielding means for normally forcing said valve-stem outward, substantially as described.

12. In a glass-blowing machine, a table, an oscillatory disk mounted thereon, one end of 50 which is provided with a mold and the other end with a rotary and longitudinally-movable hollow plunger, a hollow valve-stem through the plunger, the outer end of which is screw-threaded and provided with a mouthpiece and 55 the inner end is perforated and provided with a conical head, a nut upon the screw-threaded portion of the stem, a spring between said nut and the end of the plunger, and means for simultaneously rotating the plunger and 60 moving it longitudinally as the disk is oscillated, substantially as described.

13. In a glass-blowing machine, a support, a table rotatably mounted upon said shaft and provided with a series of glass-blowing mechanisms, each of said mechanisms being provided with a pinion, a rack upon the table for

each pinion, and a cam-shaped track secured to the support in position to engage with the upper end of said racks and move them vertically as the table is rotated, and means for 70 intermittently rotating the table, substantially as described.

14. In a glass-blowing machine, a support, a table rotatably mounted thereon, a series of glass-blowing mechanisms mounted upon the 75 table, each being provided with a pinion, a reciprocatory rack for each pinion, the upper end of each of which is provided with an arm, a track secured to the support and provided with cam-shaped grooves for engaging with 80 said arms, and means for intermittently rotating the table, substantially as described.

15. In a glass-blowing machine, a column provided with a collar intermediate its length, a table rotatably mounted upon the column 85 and provided with a hub which is adapted to be supported by said collar, a series of glass-blowing mechanisms mounted on the table and provided with means for operating them, a circular way secured to the hub of the table 90 and provided with shoulders, one for each glass-blowing mechanism, and a motor provided with means for engaging said shoulders and intermittently rotating the way and the table, substantially as described. 95

16. In a glass-blowing machine, a column provided with a collar intermediate its length, a table rotatably mounted upon the column and provided with a hub which is supported by said collar, a series of glass-blowing mechanisms upon the table provided with means for operating them, brackets secured to the hub of the table, a circular way secured to 100 said brackets, the lower edge of which is provided with notches, and a reciprocatory motor provided with a pawl for engaging with 105 said notches, substantially as described.

17. In a glass-blowing machine, a column, a table rotatably mounted thereon and provided with a series of glass-blowing mechanisms and means for operating the same, a shouldered way connected with said table, an air-cylinder adjacent thereto provided with a piston, a head upon the piston provided with a pawl for engaging with the shoulders of the 115 way and intermittently rotating the table, substantially as described.

18. In a glass-blowing machine, a column, a table rotatably mounted thereon and provided with a series of glass-blowing mechanisms and means for operating the same, a circular shouldered way connected with the table, an air-cylinder pivotally mounted adjacent thereto and provided with a piston, a head pivotally mounted on the end of the piston, and a spring-actuated pawl in the head 120 in position to engage with the shoulders of the way and intermittently rotate the table as the piston is reciprocated, substantially as 125 described.

19. In a glass-blowing machine, a base, a column and a bracket mounted thereon, a ta- 130

ble rotatably mounted on the column and provided with a series of glass-blowing mechanisms, a shouldered way connected with the table, an air-cylinder pivotally mounted upon the bracket and provided with a piston, said cylinder being provided with two inlets and one outlet, and means between the end of the piston and the way for engaging with said shoulders and rotate the table, substantially as described.

20. In a glass-blowing machine, a support, a table mounted to revolve on said support, a shaft journaled in the table and carrying a pinion, a mold and plunger carried by the shaft, a rack engaging the pinion, and means

for moving the rack as the table is revolved, as set forth.

21. In a glass-blowing machine, a support, a table mounted to revolve on the support, a shaft journaled in the table and provided with a pinion, a mold and plunger carried by the shaft, a sliding rack engaging the pinion and provided with a lateral arm at its upper end, and a cam-track on the support and with which the arm of the rack engages, as set forth. 25
